METHOD AND APPARATUS FOR HEAT SEALING

Howard A. Rohdin, Glen Ridge, N. J.

Application May 29, 1943, Serial No. 489,095

8 Claims. (Cl. 154—42)

The primary object of my invention is to provide an improved method of heat sealing, together with basic apparatus for carrying out the method, both method and apparatus being basically applicable to the manufacture of any type bag or container or to the closing of any type bag or container after the same is filled.

A further object of my invention is to provide an improved method and apparatus for heat sealing, particularly applicable to the sealing of homogeneous films such, for example, as polyvinyl alcohol, rubber hydrochloride, or polyvinyl chloride.

A further object of my invention applicable, however, only to certain types of films, is to provide a process which, while producing perfect heat seals, will also provide protection for the finished seal.

These and other objects of my invention will be made clear from the following detailed description taken in connection with the annexed drawings in which:

Figure 1 is a schematic illustration of one form of apparatus for carrying out my process in connection with step by step feeding;

Fig. 2 is a section on the line 2—2 of Fig. 1;

Fig. 3 is a partial schematic view illustrating the adaptation of the method performed by the apparatus of Figs. 1 and 2 to a continuous instead of a step by step feed.

Fig. 4 is a schematic view illustrating a specialized application of my process in which protection of the seal is provided;

Fig. 5 is a section on the line 5—5 of Fig. 4;

Fig. 6 is an elevation view showing a modification of the process illustrated in Figs. 4 and 5;

Fig. 7 is a section on the line 7—7 of Fig. 6;

Fig. 8 is a schematic illustration of the application of my process to the step by step formation of tubes on a modification of the conventional tuber;

Fig. 8a illustrates a modification of the apparatus shown in Fig. 8, this being adapted to continuous operation;

Fig. 9 is a section on the line 9—9 of Fig. 8;

Fig. 10 is a specialized form of apparatus applying my method to the production of bags sealed on three sides;

Fig. 11 is a partial plan view of the portions of Fig. 10 lying between the lines 11—11; and

Fig. 12 is an illustration of a further possible application of my process.

Heat sealing is usually accomplished by subjecting the sheets to be sealed to the simultaneous action of heat and pressure, that is, by pressing the sheets to be sealed between heated members. In such operations the pressure not only contributes to the sealing effect but also accelerates the transmission of heat from the heated pressure members to the sealable material. Heat

sealing considered without regard to the perfection of the seal has a considerable utility in that there is no necessity for waiting after the sealing step for the solvent of a wet adhesive to dry and take a permanent set. However, the materials involved in most heat sealing packages are usually so expensive that in practice heat sealing is resorted to only where an extreme perfection of seal is essential, as in vacuum packaging or in the packaging of greasy solids or liquids.

In recent years there has been an increasing use of synthetic homogeneous films in packaging operations. These films such, for example, as rubber hydrochloride, sold under the trade name of "Pliofilm," or polyvinyl chloride, sold under the trade name of "Koroseal," are produced in great variety and with numerous specialized properties of imperviousness. All such films are used in forming a heat seal by being brought above a critical temperature (critical for each particular material) at which point, under the effect of pressure, adjacent surfaces merge or coalesce into an integral, homogeneous structure. Only a few such films, under heat and pressure alone, will permanently adhere themselves to materials radically different from the films themselves, such as metal, cloth, leather, felt or paper. These films will, however, at or above their particular temperatures of plasticity temporarily adhere to such foreign substances.

In order to apply heat and pressure, heated surfaces must approach each other sufficiently to exert a substantial pressure upon sealable material placed therebetween and inevitably such surfaces must thereafter recede from each other to release the sealable material. This is true whether the heated surfaces be reciprocating members, such as sealing jaws, or cylindrical members, such as heated pressure rolls or the intermediate structure comprising opposed tractor type treads. Since the pressure members are heated, their separation must, as a practical matter, take place while the sealable material is still at an elevated temperature, in fact, at the maximum temperature attained in the particular sealing step. Under such conditions most homogeneous films will have a tacky or sticky quality with respect to the heated surfaces and the separation of these surfaces tends to separate the opposed films which are intended to be sealed. Sometimes this tendency toward separation is not sufficiently pronounced to produce an imperfect seal, but very frequently imperfect seals are thus produced and in the manufacture or closing of hundreds of millions of packages this is a very substantial element of waste, particularly when the high cost of the material involved is taken into account.

I have found that by interposing, between the heated surfaces and the sheets to be sealed, sheets

or strips of material which under no circumstances will cling to the heated pressure surfaces, I am able to avoid entirely the above described effect. Usually the interposed protective members will have surface characteristics such that not only will such members fail to adhere to the heated pressure surfaces, but they will also fail permanently to adhere to the sheets to be sealed. For some purposes, which will be described hereinafter, permanent adhesion between the protective members and the sheets to be sealed is desirable, but under no circumstances should the protective members have any affinity for the heated surfaces.

Referring now to Figs. 1 and 2, I show a pair of heated pressure jaws 10. The heating may be accomplished by means of electric coils 12 or by any other suitable means. The jaws 10 are moved toward and from each other by a toggle mechanism 11, although any other mechanism for producing the same or an equivalent motion will be equally satisfactory. Between the jaws 10 run belts 14 and 16. These belts may be formed of any material suitable relative to the particular sheets to be sealed; that is: the belts may be formed of cloth, felt, leather, paper, woven wire, or even certain synthetic materials. The belts travel in the direction of the arrow A in a step by step movement synchronized with the movement of the jaws 10 by any conventional means; that is: the belts 14 and 16 advance in the direction of the arrow A, while the jaws 10 are separated and the jaws 10 come together to exert pressure during a dwell or pause in the movement of the belts 14 and 16. Bags 18 have their walls 20 at their open mouths collapsed into a single plane and the collapsed walls 20 are fed between belts 14 and 16. In handling filled packages it will usually be convenient to have the bags travel in a vertical position, in which case the weight of the contents may be supported by a belt 22. If the bags are empty and it is merely desired to form a side or bottom seam, the bags may travel in the horizontal plane, in which case conveyor belt 22 may be eliminated.

The belts 14 and 16 carry the bags 18 to bring the mouths 20 through between the jaws 10. During a pause in the advance of the belts the jaws 10, actuated by the toggle or other suitable means 11, come together with substantial pressure. The heat of the jaws 10 is transmitted through the belts 14 and 16 to raise the temperature of the walls 20 of the bags 18 and when a sufficient temperature is attained the walls 20 coalesce to form a perfect seal. With any belts other than flat metallic ribbons, that is, belts formed of cloth, leather, felt or woven wire, etc., there is sufficient pliability in the cross section of the belts themselves to eliminate any localization of pressure due to ordinary differences of caliper in the walls 20, and this is an important factor in decreasing the opportunities for the formation of imperfect seals.

Because there is a possibility that the material of the walls 20, under the effect of heat and pressure, may adhere temporarily to the belts or members 14 and 16, the path of the belts 14 and 16 is maintained in a straight line beyond the jaws 10 for a sufficient distance to permit the walls 20 to cool below the temperature of plasticity. By the term "temperature of plasticity" I mean to include any temperature at which the material to be sealed is sufficiently plastic, tacky or adherent to form any appreciable bond between the material to be sealed and the material of the belts

or members 14 and 16. After the walls 20 have cooled below the temperature of plasticity, the bags 18 may readily be removed from the belts 14 and 16, either by separation of the belts permitting the bags 18 to drop or by the use of pickers or strippers, should there be sufficient residual adhesion of the walls 20 to the belts 14 and 16 to warrant the use of such means. A slight strain at such a temperature has no effect upon the perfection of the seal which is designed and dimensioned to withstand, when cool, a far greater strain than is occasioned by detachment from the belts 14 and 16. The coalescence of the meeting faces of the walls 20 will be complete because of the cooling action. The belts themselves are in substantially non-pressure contact with the bags throughout their travel. Sealing pressure is applied wholly by the jaws.

In Fig. 3, I show belts 30 and 32 and a collapsed bag mouth 34 between the belts, all passing between heated pressure rollers 36. The surfaces of the rollers 36 separate immediately following the application of pressure at the nip of the rollers 36. The belts 30 and 32 continue in a straight line, after passing through the nip of rollers 36, for a sufficient distance to permit cooling the bag mouth 34 below the temperature of plasticity. As any substantial speed is attained it is obvious that there will be very little time in which the rollers 36 may act to raise the temperature of the bag mouth 34. This, however, may be compensated for by using several sets of rollers 36 or by pre-heating the bag mouth 34 before it reaches the nip of rollers 36.

In Figs. 4 and 5, I illustrate a special application of my invention which may be used where, for protective reasons, it is desired to reinforce and shield the heat sealed bag mouth. This particular application has utility only where the material to be heat sealed is of such nature as to be sealable to the protective strips or members. Obviously, the most advantageous arrangement is where the protective strips, under the action of the same heat and pressure which effects the chief seal, will laminate themselves to the material of the bag mouth, and it is such a condition that I illustrate in Figs. 4 and 5. It is entirely possible, however, to apply either to the bag mouths or to the reinforcing strips, or both, a fluid adhesive which will insure lamination of the protective strips to the bag mouth. In most cases, paper will be most satisfactory material for the protective strips.

In Figs. 4 and 5, I indicate pressure jaws 40, electrically heated by coils 42, and I also indicate a reel 44 supplying a protective strip 46 and a reel 48 supplying a protective strip 50. Bags are fed between strips 46 and 50 and pass between the members 40, which apply heat and pressure as hereinbefore described with respect to jaws 10 of Figs. 1 and 2. The strips 46 and 50 are thus permanently adhered to the bag mouths and form a chain of sealed bags. This chain is drawn forward by draw rolls 52 for a sufficient distance from the jaws 40 to permit the requisite cooling to take place. Immediately after the draw rolls 52 is a cutter 54 which severs the strips 46 and 50 between bags. The apparatus illustrated in Figs. 4 and 5, like that shown in Figs. 1 and 2, will operate with the bags in a vertical plane when closing filled packages and will usually operate with the bags in the horizontal plane when forming seams during the manufacture of the bags.

In Figs. 6 and 7, I illustrate a modification of the form of Figs. 4 and 5. In this case a reel 60 supplies a strip 62 which passes through a folder

64 which bends the strip 62 into a U-shaped cross section. Bags 66 are supported on a belt 68 and are placed with their mouths 70 inside the U-shaped cross section of folded strips 62. The strip 62, containing the bag mouth 70, then passes between a pair of heated rollers 72. Obviously pressure jaws or a pressure tractor could be substituted for the heated rollers. The result is a chain of bags joined by the folded strips 62. The chain is fed by draw rollers 74, and cutters 76 operate to sever the strip 62 between bags. The draw rollers 74 are synchronized with the belt 68 and the cutters 76 by any conventional means. There must, however, be sufficient travel between the heated pressure rolls 72 and the draw rolls 74 to permit the requisite cooling to take place.

In Fig. 8, I illustrate the application of my process to the formation of side or center seams on a conventional tuber. A web of thermoplastic material 80 is drawn from a reel 82 and passed over a roller 84, thence over a tuber 86, where its margins are brought into overlapping relationship to form a tube. Ordinarily in the formation of such a tube it is brought into flattened condition as rapidly as possible. In the application of my process, however, I form the tuber 86 in such manner as to maintain, for an appreciable distance, the maximum cross sectional area of the tube. Within the tuber 86 I place a standard 88 which supports a pressure member 90 heated by coils 92. Above the tuber 86 I provide a reciprocating pressure member 94 heated by coils 96. A belt 98 passes under the pressure member 94 between it and the overlapped margins 100 of the web 80, while a belt 102 passes above the pressure member 90 and below the overlapped margins 100. The web 80 in this form advances step by step and during each pause in the forward movement the upper pressure member 94 is brought down to compress and heat the margins 100 of the web 80 between the belts 98 and 102. As mentioned before, there must be a sufficient undisturbed travel of the belts 98 and 102 following the action of the pressure members 90 and 94 to permit the requisite cooling to take place, and the forward steps of the web 80 will usually be calculated with reference to the length of the pressure members 90 and 94 to assure the formation of a continuous seam. Following the formation of the seam and its discharge from the belts 98 and 102, the tube is brought into conventional flattened condition, at which time consecutive bag lengths are severed therefrom and one end of each length may be closed by any of the methods heretofore discussed.

Obviously, either or both of the belts 98 and 102 may be eliminated in favor of strips such as 46 and 50 of Fig. 4, where reinforcement is desired and the nature of the material makes the substitution possible. This also applies in the case of Fig. 8a hereinafter described.

In Fig. 8a, I illustrate a modification of Fig. 8 in which a web 110 passes over a tuber 112 in which is arranged a heated pressure roller 114 and its associated belt 116, while above the tuber is a heated pressure roller 118 and a belt 120. Such an arrangement offers the opportunity for continuous travel of the web 110 as distinct from the step by step movement of the web 80 of Fig. 8.

In Figs. 10 and 11, I illustrate a further application of my invention to the manufacture of flat bags of the type which are produced by forming seams along three consecutive edges. In this application a web of thermoplastic material 130 is drawn from a reel 132 and superimposed upon a

web 134 of similar material drawn from a reel 138. The superimposed webs 130 and 134 then pass between a pair of belts 138 which completely overlie the superimposed webs. The belts 138 and the webs 130 and 134 then pass between heated pressure rollers 140. These rollers have longitudinal raised portions 142 and a central circumferential raised portion 144 and their effect is to form, in the superimposed webs, lines of sealing 146, 148 and 150. Rollers 152 act as guides for the belts 138 and also as draw rollers for the webs 130 and 134. As the webs 130 and 134 emerge from the nip of the rollers 152 they pass between rotary cutters 154 which sever the webs 130 and 134 midway of the sealed areas 146, 148 and 150 to form individual bags 156. The travel between heated pressure rollers 140 and draw rollers 152 must be sufficient to permit the requisite cooling. Obviously, this particular method is adaptable to step by step travel of the webs 130 and 134, in which case flat bed pressure members would be utilized instead of rollers 140. It is clear that for the belts 138 there could be substituted an equivalent pair of continuous webs in the manner illustrated in Fig. 4, wherever the nature of the material admits. If this be done, not only the seam but the entire package is protected by the lamination of the protective webs to the heat sealable material.

In Fig. 12, I illustrate the adaptation of my invention to a form of sealing which has been successful heretofore but which has required the use of a paper outer ply laminated to contacting inner plies of thermoplastic material. In Fig. 12, I show member 160 heated by coils 162 and having a groove 164 in its active face. Opposed to the member 160 is a member 168 heated by coils 170 and having on its active face a rib 172 in alignment with the groove 164 of the member 160. Bags 174, formed of thermoplastic material and having collapsed mouths 176, are passed between a belt 178 adjacent to member 160 and a belt 180 adjacent the member 168. The clearance between members 160 and 168 is such that the rib 172 will flex and bend the belts 178 and 180 and the bag mouths 176 into the groove 164 of the member 160. This flexure assures sealing contact between the inner surfaces of the bag mouths 176, and for materials having a low temperature of plasticity, the pressure occasioned by the flexing is sufficient to effect a seal. Such materials, however, have a pronounced tendency toward tackiness and would be distorted and the efficacy of the seal destroyed were it not for the protection afforded by the belts 178 and 180. The belts should remain, naturally, in undisturbed contact with the bag mouth 176 for a sufficient period following the action of members 160 and 168 to permit the requisite cooling. This is done by prolongations of members 160 and 168, such prolongations being thermally separated from said heated members. For filled bags a supporting or carrying belt 182 should be provided, in which case the bags will travel in the vertical. Naturally, for empty bags the travel may be in the horizontal, in which case the carrier belt may be eliminated.

Throughout this specification I have described pairs of pressure members in which both members are heated. I do not, however, intend to be limited to such an arrangement, since for my purposes only one of the pressure members need be heated, and where one member is hot and the other at room temperature it may sometimes be

possible to dispense with one of the protective belts or members.

In the subjoined claims I refer to the sealing of "sheets of material." These may be simply sheets which it is desired to laminate or they may be the contacting walls of a bag mouth, gusseted or non-gusseted, and of single or multiple ply construction.

While I have described my invention with reference to certain specific applications illustrated herein, I do not intend to be limited thereto but only as set forth in the subjoined claims which are to be broadly construed.

What is claimed is:

1. A method of heat sealing which comprises: superimposing a plurality of sheets to be sealed; applying to the external surfaces of said superimposed sheets a pair of members; applying heat and pressure to said members; and simultaneously withdrawing both the heat and pressure from said members while maintaining said members in undisturbed substantially non-pressure contact with said sheets until cooled below the temperature of plasticity, and thereupon separating said members to release said sheet, said members having the property, relative to the source of said heat and pressure and relative to said sheets, of not sticking either to said source or said sheets.

2. A method of heat sealing comprising: superimposing a plurality of sheets to be sealed, applying to the external surfaces of said sheets a pair of members; advancing said sheets and said members to a predetermined location and there applying heat and pressure to said members with said sheets therebetween simultaneously withdrawing both the heat and pressure from said members, and advancing said members and said sheets in substantially non-pressure contact beyond said sealing point until said sheets have cooled below the temperature of plasticity, and thereupon separating said members to release said sheet, said members having the property, relative to the source of said heat and pressure and relative to said sheets of not sticking to said source or to said sheets.

3. A method of heat sealing which comprises: superimposing a plurality of sheets to be sealed; applying to the external surfaces of said sheets a pair of members; bringing together a pair of heated surfaces with said members and said sheets therebetween to exert a sealing pressure thereon; thereafter separating said heated surfaces; and maintaining said members in undisturbed substantially non-pressure contact with said sheets during the separation of said surfaces and until said sheets have cooled below the temperature of plasticity, and thereupon separating said members to release said sheet, said members having the property, relative to said heated surfaces and relative to said sheets of not sticking to said surfaces or said sheets.

4. A method of heat sealing comprising: superimposing a plurality of sheets to be sealed; applying to the external surfaces of said sheets a pair of members; advancing said sheets and said members between a pair of heated surfaces; bringing said heated surfaces toward each other with said sheets and members therebetween to exert a sealing pressure thereon; thereafter separating said heated surfaces; maintaining said members in undisturbed substantially non-pressure contact with said sheets during the separation of said heated

members and until said sheets have cooled below the temperature of plasticity and advancing said members and said sheets beyond the meeting point of said heated surfaces, and separating said members after said sheets have thus cooled to release said sheets, said members having the property relative to said heated surfaces and relative to said sheets of not sticking to said surfaces or said sheets.

5. A method of heat sealing which comprises: superimposing a plurality of sheets to be sealed; covering each external surface of the superimposed sheets with a protective ply; applying heat and pressure to said protective ply and said sheets; and simultaneously withdrawing both the heat and pressure from said ply while maintaining said ply in undisturbed substantially non-pressure contact with said sheets until cooled below the temperature of plasticity and thereupon separating said plies from said sheets to release said sheets, said ply having the property, relative to the source of said heat and pressure and relative to said sheets, of not sticking to said source or said sheets.

6. A method of heat sealing comprising: superimposing a plurality of sheets to be sealed, covering each external surface of the superimposed sheets with a protective ply; advancing said sheets and said ply to a predetermined location and there applying heat and pressure to said ply and said sheets, simultaneously withdrawing both the heat and pressure and advancing said ply and said sheets in substantially non-pressure contact beyond said sealing point until said sheets have cooled below the temperature of plasticity and thereupon separating said plies from said sheets to release said sheets, said ply having the quality relative to the source of said heat and pressure and relative to said sheets of not sticking to said source or to said sheets.

7. Apparatus for heat sealing comprising: a pair of opposed, flexible members, means for advancing said members with superimposed heat sealable plies therebetween; means for applying heat and pressure to said heat sealable plies through said members, such means being located along the path of advance of said members, means operable after the operation of said heat and pressure applying means for separating said members from said heat sealable plies and the action of said member separating means being deferred until said heat sealable plies have cooled below their temperature of plasticity, said members having the property, relative to said plies and to said heat and pressure applying means of not sticking either to said plies or to said heat and pressure applying means.

8. A method of heat sealing comprising: superimposing sheets having both surfaces of each sheet heat sealable; advancing said superimposed sheets between a pair of protective members; advancing said members concurrently with said sheets; applying heat and pressure to said members and thereby to said sheets to seal said sheets together during said advance; terminating the application of heat while continuing said advance and maintaining said members in undisturbed contact with said sheets during such advance until said sheets have cooled below sealing temperature and thereafter separating said members to release said sheets.

HOWARD A. ROHDIN.
